UNITED STATES PATENT OFFICE

2,595,506

ADJUSTABLE DOOR JAMB

John W. Backman, Los Angeles, Calif., assignor to
 Southern California Glass Co., Inc., a corporation of California

Application April 7, 1948, Serial No. 19,543

3 Claims. (Cl. 189—46)

1

In the hanging of hinged doors the difficulty is frequently encountered of either or both side walls of a doorway not being truly vertical, and hence, a door cannot be properly hung therein until the walls are made vertical or the door jambs secured to the walls so as to compensate for this defect. Even where the side walls of a doorway are exactly vertical to begin with, in time they become non-vertical by reason of warpage or settling of the wall or floor structure, so that the jambs are no longer vertical. This results in sagging of the door causing it to bind in the doorway and/or to prevent latching of the door. Especially does this condition arise in the doorways of shower stalls where the surrounding structures are subjected to the dampening action of the water from the showers.

It is a purpose of my invention to provide a jamb for doors which is readily adjustable to compensate for any deviation from the vertical or either side of a doorway, so that the jamb as presented to a door is exactly vertical. In practice my invention is preferably embodied in both the door-hanging jamb and the latch jamb, and thus a door can not only be properly hung, but when closed will be caused to properly engage the latch jamb so that the latch bolt on the door can engage the keeper on the jamb to secure the door in closed position.

It is also a purpose of my invention to provide an adjustable door jamb particularly applicable to doors made up of extruded metallic frames with glass panels therein, such as shower stall doors, store doors and the like.

A further purpose of my invention is the provision of a door jamb embodying a pair of rails one of which is to be secured to a side wall of a doorway and the other of which confronts the door, and the latter rail so associated with the wall rail that it can be adjusted laterally to a true vertical position irrespective of the position of the wall rail in relation to the vertical.

I will describe only one form of adjustable jamb embodying my invention and as applied to one form of doorway and door, and will then point out the novel features thereof in claims.

In the accompanying drawings:

Fig. 1 is an elevational view of a shower stall and door therefor having applied thereto one form of adjustable jamb embodying my invention.

Fig. 2 is an enlarged horizontal sectional view taken on the line 2—2 of Fig. 1.

Fig. 3 is an exploded view showing in perspec-

tive the parts of the door jamb, the rails of which are shown fragmentarily.

Fig. 4 is an enlarged fragmentary elevational view, partly in section, of one side wall of the doorway, the door, and that adjustable jamb upon which the door is hung.

Fig. 5 is an enlarged sectional view taken on the line 5—5 of Fig. 4, but with the door swung to open position, the corresponding fastening screw removed, and a screw-driver applied to the spacing element of the jamb for adjustment thereof.

With specific reference to the drawings and particularly to Fig. 1, I have here shown a doorway W of a shower stall, and a door D hung in the doorway, the side walls 15 and 16 of the latter having secured thereto adjustable jambs J and J1 constructed in accordance with my invention. The door is hingedly hung on the jamb J, and hence, will be referred to hereinafter as the hanging jamb as distinguished from the jamb J1 which is the latch or abutment jamb and as usual carries a keeper for a latch on the door to latch the door in closed position, neither of which is shown. The door being for a shower stall is made up of an extruded metal frame F containing a glass panel P.

Each jamb J or J1 is made up of a pair of rails R and R1, the rail R for the jamb J being secured to the side wall 15 and the rail R1 transversely telescoped on the rail R and confronting one side portion 17 of the frame F. Both rails may be made of extruded metal, the rail R being of U-form in cross-section to provide parallel spaced flanges 18 and a connecting web 19 the edges of which web are provided with coextensive ribs 20. The rail R1 which is co-extensive in length with the rail R, is likewise of U-form in cross-section to provide parallel spaced flanges 21 connected by a web 22 having a co-extensive lip 23 on one edge thereof. The inner side of the web 22 has a plurality of longitudinally extending ribs 24 on its inner side which serve to reinforce the web and portions of which engage spacing elements as will be later described herein.

The spacing of the flanges 21 is such that the rail R can be slidably fitted transversely therebetween, and thus the rail R1 is telescopically mounted on rail R to allow adjustment thereof transversely on the rail R. The hanging jamb J is secured at intervals along its length to the wall 15 by fastening members 25 such as the screws illustrated, the webs 19 and 22 being formed with registering openings 26 and 27, respectively, through each pair of which

a screw 25 freely extends for securing the rail R to the wall 15. Screw-threaded within each opening 26 is a spacing element 28 which may be in the form of a metal sleeve with transverse slots 29 in one end thereof. The tubular form of the element allows the respective screw 25 to be extended freely through the element and into the wall 15 so that it will not interfere with removal thereof when required.

Each element 28 and its respective screw 25 may be said to constitute an adjusting unit for the rail R1, and as illustrated in Fig. 1 there are three such units properly spaced along the length of the rail. The door D is hung on the jamb J by a hinge H which is coextensive in length with the door and jamb, and with one leaf thereof secured to the side frame portion 17 and the other to the web 22.

Now if the wall 15 deviates from the vertical such as is illustrated in Figs. 1 and 4, the rail R of the hanging jamb J will of necessity occupy a corresponding position. To compensate for this deviation the rail R1 can, by transverse adjustment thereof on the rail R, be caused to assume a true vertical position so that the hinge H will likewise occupy a vertical position, and thus the door can be properly hung in the doorway.

Such adjustment of the rail R1 is afforded by the spacing elements 28 and in the following manner. The door D is first swung to open position (see Fig. 5), and the screw 25 for the center adjusting unit is removed from the wall and jamb, as is illustrated in Fig. 5. This allows access to the respective spacing element 28 so that the shank 30 of a screw-driver may be extended through the opening 27 and into the slots 29. By now turning the screw-driver in the proper direction the element 28 is screwed outwardly of the rail R and this moves the medial portion of the rail R1 outwardly through pressure on the ribs 24, so that the element 28 now acts as a fulcrum for the rail. This allows of the necessary lateral adjustments of the top and bottom units to bring the end portions of the rail R1 into vertical position, and such adjustments are performed successively by first removing the screws and then turning the spacing elements in one direction or the other as the case requires.

These adjustments are maintained by returning the screws thereof into the rails and wall so as to hold the rail R1 firmly against the spacing elements 28. The final operation consists in adjusting the center spacing element until the medial portion of the rail R1 is brought into vertical position, and thus the rail is now positioned vertically from end to end so that the door as hung thereon by the hinge H will swing about a true vertical axis.

Should the other wall 16 of the doorway deviate from the vertical, the rail R1 of the latch jamb J1 can be caused to assume a true vertical position through adjustment of the corresponding spacing elements 28 in the manner described in connection with the jamb J.

In this instance, the lip 23 acts as an abutment to define the closed position of the door D, and the rail R1 being in true vertical position, and the side frame portion 17 being likewise in a vertical position by reason of the afore-

described adjustment of the jamb J, it becomes clear that where the door is provided with the usual latch, and the rail R1 with the usual keeper, the two are positioned to engage each other when the door is closed to latch the latter in such closed position.

Although I have herein shown and described only one form of adjustable door jamb embodying my invention, it is to be understood that various changes and modifications may be made therein without departing from the spirit of my invention and the spirit and scope of the appended claims.

I claim:

1. A door jamb, including: a pair of rails telescoped transversely one within the other; an element screw-threaded transversely in one rail and abutting the other rail; and a fastening member extending through said rails and said element and adapted to extend into a side wall of a doorway for securing the rails to said wall, and the rails to each other in that telescoped spaced relationship as defined by adjustment of said element in its respective rail, said element being tubular and having tool receiving means in that end abutting said other rail for turning the element to adjust the same in the respective rail:

2. An adjustable door jamb construction adapted to be mounted in an opening in a wall, comprising: a first rail having a plurality of spaced holes transversely therethrough with the walls thereof threaded; a second rail telescoping transversely on the first rail and provided with holes transversely aligned with the holes in the first rail; a tubular externally threaded abutment mounted in each of the threaded holes in the first rail and adjustable therein; and screws positioned in the holes in the second rail with their heads engaging the second rail and their shanks passing freely through the tubular abutments and adapted for threaded engagement with the wall so that under adjustment thereof the second rail is brought into direct engagement with the tubular abutments whereby the door jamb is securely held against the wall of the door opening with the second rail held in adjusted relation to the first rail.

3. A door jamb construction as embodied in claim 2, wherein each of said abutments has an inside diameter less than that of the respective hole in the second rail and tool-receiving slots in the end thereof confronting the hole and accessible therethrough by a screw-driver for turning the abutment.

JOHN W. BACKMAN.
